(57) **CLAIM**

The ornamental design for an optical connector cleaner, as shown and described.

DESCRIPTION

FIG. 1 is a top, front perspective view of an optical connector cleaner showing our new design;

FIG. 2 is a bottom front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a front perspective view thereof, with the cap in a stored position;

FIG. 10 is a rear perspective view of FIG. 9;

FIG. 11 is a front elevational view of FIG. 9;

FIG. 12 is a top plan view of FIG. 9;

FIG. 13 is a left side elevational view of FIG. 9; and,

FIG. 14 is a bottom perspective view of FIG. 1, with the cap lid shown in an opened condition.
